 9 Claims. (Cl. 260—256.5)

The present invention relates to sulfonamides and more particularly to 2 - benzene - sulfonamido - 5-alkoxy-pyrimidines.

It is known that, in addition to sulfaureas, certain heterocyclic substituted sulfonamides, e.g. 5-sulfa-2-alkyl-1,3,4 - thiadiazoles and 5 - sulfa-2-alkyl-1,3,4-oxadiazoles, also exhibit a blood sugar depressant activity (cf., e.g., Medizin und Chemie, vol. VI (1958), p. 61 ff.).

In spite of a large number of experiments, no further heterocyclic substituted sulfonamides other than the specified compounds have been reported with an antidiabetic effect which can be utilized in practice.

It is therefore an object of the present invention, to provide heterocyclic substituted sulfonamides useful in the therapy of diabetes. A further object is the provision of sulfonamides having an anti-diabetic effect, but no undesirable bacteriostatic properties. Further objects will become apparent as the present specification proceeds.

We have found that sulfonamides are obtained with an intensive and long lasting blood sugar depressant activity, when 2-amino-5-alkoxy-pyrimidines, in which the alkyl residue has a straight or branched chain and possesses 2 to 5 carbon atoms, are reacted in the presence of acid binding agents with benzene sulfochloride or with benzene sulfochlorides which are substituted in the benzene nucleus by lower alkyl and/or alkoxy residues and/or halogen atoms, or when the reaction products of the Vilsmeier reaction between alkoxyacetaldehyde acetals or between 1,2-dialkoxyethylenes, in which the alkyl residue has a straight or branched chain and possesses 2 to 5 carbon atoms, and N,N-disubstituted formamides and inorganic acid chlorides, are condensed in the presence of basic condensation agents, with benzene sulfonylguanidine or benzene sulfonylguanidines which are substituted in the benzene nucleus by lower alkyl and/or alkoxy groups and/or halogen atoms.

The 2-amino-5-alkoxy-pyrimidines employed as starting materials for the first mentioned method of execution can be prepared by the process described in the copending application Serial No. 54,836, filed September 9, 1960, and now abandoned.

Tertiary organic bases, such as pyridine or triethylamine, are the preferred suitable acid-binding agents.

Dimethyl formamide is the preferred suitable N,N-disubstituted formamide in the sense of the second method of execution, and phosgene is the preferred suitable inorganic acid chloride.

During this form of execution, the condensation is carried out within a temperature range of 50-200° C., preferably in an aliphatic alcohol; alkali metal alcoholates or alkali metal hydroxides are particularly suitable as condensation agents.

The 2 - benzene-sulfonamido-5-alkoxy-pyrimidines obtained according to the process lead to a distinctly exhibited and long lasting depression of the blood sugar level upon administration to experimental animals (rabbit, dog). Thus, a single oral administration of 250 mg./kg. of 2 - (4' - methylbenzene - sulfonamido) - 5 - n-propoxy-pyrimidine to a rabbit with normal metabolism

2

can achieve a 54% depression in the blood sugar level within the first 6 hours. The depression in the blood sugar level is still maintained to the same extent 24 hours after the start of the experiment. By comparison, a maximum depression in the blood sugar level of 45% can be obtained in 5 hours under the same experimental conditions with 250 mg./kg. of N-(4-aminobenzene-sulfonyl)-N'-n-butyl-urea.

The 2-benzene-sulfonamido-5-alkoxy-pyrimidines have a superior effect compared with the 2-sulfanilamido-5-alkoxy-pyrimidines with 2 to 4 carbon atoms in the alkyl residue, as known from the copending application Serial No. 54,853, filed September 9, 1960, and now abandoned. Moreover, they are also distinguished by their lack of undesirable bacteriostatic properties.

Example 1

14 g. (0.1 mole) of 2-amino-5-ethoxy-pyrimidine are dissolved in 100 ml. of pyridine. 17.5 g. (0.1 mole) of benzene sulfochloride are added dropwise with stirring and on cooling by ice/common salt. The temperature is allowed to rise gradually, and it is stirred overnight at room temperature. After heating to 100° C. bath temperature for one hour, the pyridine is distilled off in vacuo, the residue is digested with dilute hydrochloric acid on the water bath, and after cooling with ice, it is filtered off with suction. After reprecipitation from aqueous ammonia/acetic acid, the 2-benzene-sulfonamido-5-ethoxy-pyridine is obtained in the form of colourless crystals of M.P. 174-175° C. at a yield of 17.5 g.=62.5% of the theoretical.

By analogy, 2 - (4' - methylbenzene - sulfonamido) - 5 - ethoxy-pyridine of M.P. 197° C. is obtained from 2-amino-5-ethoxy-pyridine and p-toluene sulfochloride;

35 2 - (2' - methylbenzene-sulfonamido)-5-ethoxy-pyrimidine of M.P. 181° C. from 2-amino-5-ethoxy-pyrimidine and o-toluene sulfochloride;

40 2 - (4' - methoxybenzene - sulfonamido) - 5 - ethoxy-pyrimidine of M.P. 196° C. from 2 - amino - 5 - ethoxy-pyrimidine and p-methoxybenzene sulfochloride;

45 2-(4'-chlorobenzene-sulfonamido)-5-ethoxy-pyrimidine of M.P. 183-184° C. from 2-amino-5-ethoxy-pyrimidine and p-chlorobenzene sulfochloride;

50 2-(4'-methylbenzene-sulfonamido)-5-n-propoxy-pyrimidine of M.P. 196-197° C. from 2-amino-5-n-propoxy-pyrimidine and p-toluene sulfochloride;

55 2 - (4' - methylbenzene - sulfonamido)-5-n-butoxy-pyrimidine of M.P. 186-187° C. from 2-amino-5-isopropoxy-pyrimidine and p-toluene sulfochloride;

60 2 - (4' - methylbenzene - sulfonamido)-5-n-butoxy-pyrimidine of M.P. 179-180° C. from 2-amino-5-n-butoxy-pyrimidine (M.P. 72-74° C.) and p-toluene sulfochloride.

Example 2

55 80 g. (0.25 mole) of ethoxy-acetaldehyde diethylacetal are brought to reaction in 300 ml. of methylene chloride with 73 g. of dimethyl formamide and 150 g. of phosgene in analogy to the directions stated by Z. Arnold and F. Sôrm (Coll. Czechoslovak Chem. Commun. 23 (1958), 452). After neutralization with a methanol solution of sodium methylate and evaporation of the solvent in vacuo there are obtained 82.5 g. of an oily reaction product, which is added dropwise to a suspension of 96 g. (0.45 mole) of p-methylbenzene-sulfonylguanidine in 1000 ml. of ethanol containing 46 g. of dissolved sodium. After boiling under reflux for 8 hours, the ethanol is distilled off in vacuo. The residue is digested with cold water, non-reacted p-methylbenzene-sulfonylguanidine is filtered off with suction, and the filtrate is acidified with acetic acid. 2 - (4' - methylbenzene - sulfonamido)-5-ethoxy-pyrimidine, which on reprecipitation from aqueous am-

monia/acetic acid melts at 197° C., is obtained in good yield.

By analogy, 2 - (2' - methylbenzene - sulfonamido)-5-ethoxy-pyrimidine of M.P. 184° C. is obtained, starting from ethoxy-acetaldehyde diethyl-acetal, by Vilsmeier reaction with dimethyl formamide and phosgene, and by condensation of the reaction product with 2-methylbenzene-sulfonylguanidine;

2-benzenesulfonamido-5-n-propoxy-pyrimidine of M.P. 181-182° C., starting from n-propoxy-acetaldehyde di-n-propyl-acetal, by Vilsmeier-Haak reaction with dimethyl formamide and phosgene, and by condensation of the reaction product with benzene-sulfonylguanidine.

We claim:

1. A 2-benzene - sulfonamido - 5-alkoxy-pyrimidine of 15
the formula:

- 4
- 5   3. 2 - (4' - methylbenzene - sulfonamido)-5-ethoxy-pyrimidine.
 4. 2 - (2' - methylbenzene - sulfonamido)-5-ethoxy-pyrimidine.
 5   5. 2 - (4' - methoxybenzene-sulfonamido)-5-ethoxy-pyrimidine.
 6. 2 - (4 - chlorobenzene - sulfonamido)-5-ethoxy-pyrimidine.
 7. 2 - (4' - methylbenzene-sulfonamido)-5-n-propoxy-pyrimidine.
 10   8. 2 - (4' - methylbenzene-sulfonamido)-5-isopropoxy-pyrimidine.
 9. 2 - (4' - methylbenzene - sulfonamido)-5-n-butoxy-pyrimidine.
